PLASTIC SHEETING OR THE LIKE

Eliot S. Mover, Brighton, Mass., assignor to
Bunny Bear Inc., Everett, Mass., a corporation
of Massachusetts

Application May 12, 1953, Serial No. 24,972

Term of patent 14 years

(Cl. D92—1)

To all whom it may concern:

Be it known that I, Eliot S. Mover, a citizen of the United States of America, residing at Brighton, county of Suffolk and Commonwealth of Massachusetts, have invented a new, original, and ornamental Design for Plastic Sheeting or the like, of which the following is a specification, reference being had to the accompanying drawing forming a part thereof.

The drawing is a plan view of plastic sheeting or the like showing my new design. A design unit is shown within the broken lines and is repeated as indicated.

I claim:

The ornamental design for plastic sheeting or the like, substantially as shown and described.

ELIOT S. MOVER.
